UNITED STATES PATENT OFFICE.

MICHAEL JOHN METZLER, OF ROCHESTER, NEW YORK.

PRESSING PAD.

Application filed June 21, 1921. Serial No. 479,408.

To all whom it may concern:

Be it known that I, MICHAEL J. METZLER, a citizen of the United States, and resident of Rochester, in the county of Monroe and 5 State of New York, have invented certain new and useful Improvements in Pressing Pads, of which the following is a specification.

The present invention relates to pressing 10 pads and more particularly to the type designed for positioning on pressing boards for the purpose of pressing those portions of the garment which it is impossible to press upon the flat face of the board, an 15 object of this invention being to produce a pad which will permit the pressing of any portion of a man's coat and particularly the type having form fit sides.

To these and other ends, the invention consists of certain parts and combinations of 20 parts, all of which will be hereinafter described, the novel features being pointed out in the appended claims.

In the drawings:

25 Fig. 1 is a plan view of the pad;
Fig. 2 is an edge view;
Fig. 3 is a view of one end of the pad;
Fig. 4 is a section on the line 4—4, Fig. 1;
Fig. 5 is a plan view of one of the side 30 pieces of the pad;

Fig. 6 is a fragmentary view of the edge piece; and

Fig. 7 is a section on the line 7—7, Fig. 1.

The pad is constructed of two facing 35 pieces 1 and an edge strip 2, the facing pieces being secured to opposite edges of the edge strip by seams 3 and the whole enclosing a filler 4 of soft yielding material. The facing pieces have on opposite sides, recessed portions 1^a and from these recessed portions the edges converge at 1^b toward a curved end 1^c. On the opposite sides of the recessed portions, the edges of the facing pieces diverge at 1^d to a wide curved end portion 1^e. The edge strip 2 unites the entire side edges of the two facing pieces 1 and this strip is of uniform width. In order to restrict the width of the strip 2 at the recess portions 1^a, the facing pieces are 40 secured to the strip 2 at the recessed portions along lines 2^a which are closer together than the seams throughout the greater portions of the strip. This produces a thinner and more curved effect at the recessed portions 1^a. 45 The edge strip 2 is also slit at the point 1^e

and the walls of the slit are secured together to produce a seam 2^b. This causes a thinner and more pointed end on the pad.

The coat is pressed by bringing the side 50 seams alternately against opposite sides of 60 the pad so that the coat lies in contact at the side seams with the sides of the pad. After the side seams have been pressed, the narrow end 1^c is introduced in the shoulders of the 65 coat and the shoulders pressed over said narrow end. The collar is pressed by fitting it about the larger or wider end 1^c. The back of the coat, of course, may be pressed upon the flat faces of the pad, as may also 70 the front of the coat.

From the foregoing it will be seen that 75 there has been provided a pad which has a recess in opposite sides nearer one end than the other. The sides converge from the recesses toward the nearer end and diverging 80 from the recesses toward the other end. The pad is thinner at the nearer end and at opposite ends to the recess than at the other portions of such pad. This arrangement permits the pressing of a form fit coat in an 85 effective manner as portions of the coat which have been heretofore difficult to press may be readily pressed.

What I claim as my invention and desire 90 to secure by Letters Patent is:

1. A pressing pad having recesses in opposite sides, nearer one end of the pad than the other, the sides of the pad converging toward the nearer end and diverging toward the farther end and opposite faces of the 95 pad between the diverging sides being substantially flat.

2. A pressing pad having recesses in opposite sides, nearer one end of the pad than the other, the edges of the pad converging toward the nearer end and diverging toward the other end, and the nearer end being thinner than the farther end and the pad also being thinner on opposite sides at the recesses than at those portions of the sides 100 away from the recesses and the opposite faces of the pad being substantially flat from the recesses to the farther end.

3. A pressing pad comprising two facing 105 pieces, each provided with recesses in opposite edges nearer one end of the facing pieces than the other, the opposite edges of the facing pieces converging from said recesses toward the nearer end and diverging from said recesses toward the farther end 110

and the opposite faces of the pad being substantially flat from the recesses to the farther end.

4. A pressing pad comprising two facing pieces, each provided with recesses in opposite edges nearer one end of the facing pieces than the other, the opposite edges of the facing pieces converging from said recesses toward the nearer end and diverging

from said recesses toward the farther end 10 and the opposite faces of the pad between the diverging edges and the farther end being substantially flat, an edge strip uniting the facing pieces, said edge strip being narrower at the recesses and at the end nearer 15 the recesses than at its other portions.

MICHAEL JOHN METZLER.
